UNITED STATES PATENT OFFICE.

RUPERT S. SCHEIBLEIN, OF MERCHANTVILLE, NEW JERSEY.

MACHINE FOR CLEANING AND WAXING PHOTOGRAPHIC FILMS.

1,300,656.

Specification of Letters Patent. Patented Apr. 15, 1919.

Application filed April 27, 1916. Serial No. 93,864.

To all whom it may concern:

Be it known that I, RUPERT S. SCHEIBLEIN, a citizen of the United States, residing at Merchantville, in the county of Camden and State of New Jersey, have invented certain new and useful Improvements in Machines for Cleaning and Waxing Photographic Films; and I hereby declare that the following is a full, clear, and exact description thereof, reference being had to the accompanying drawings, which form part of this specification.

This invention is a novel machine for cleaning and waxing films, and is intended to be used in connection with so called moving picture machines, and its object is to provide means whereby the long ribbon films may be cleaned and waxed during their passage through the machine. The invention provides novel means for brushing the film, then wiping the film, and then waxing the perforated edges of the film, so that such perforated edges will not tear when the film is passed through the projecting machine. By use of this invention the picture projected from the films will be clearer, the life of the film will be greatly increased and the snapping and cracking noises which are ordinarily attendant upon the operation of such films will be obviated, or very materially lessened.

One practical embodiment of the invention is illustrated in the accompanying drawings, but the invention is not limited to the specific construction shown as, when understood, others can readily adopt and embody the same in other specific forms.

I will explain the invention with reference to said drawings, and then set forth in the claims the essential features and combinations of parts for which protection is desired.

In said drawings:

Figure 1 is a top plan view of the complete machine with the film removed.

Fig. 2 is a longitudinal sectional view of the machine on the line 2—2, Fig. 1, showing the parts in operative position in full lines and with a section of film thereon.

Fig. 3 is a front end view of the machine. Fig. 4 is a detail vertical section on line 4—4 Fig. 2. Figs. 5 and 6 are details.

The operative parts of the machine are mounted upon a base plate 1, which may be attached to any suitable support. From this base rise side members 1^a between

which, at the rear side of the attachment, is a table portion 1^b above which the sides 1^a slightly project. This table is adapted to support a wiper 2, which may be of felt, or other suitable material, and over which the film F is passed.

Above the film and table is a second wiper 2^a, similar to wiper 2. Wiper 2^a is yieldingly pressed down toward wiper 2 and upon the film by means of a presser plate 3 which is provided with upturned ends 3^a by which it may be supported in a plate 3^b having ears 3^c hinged to upwardly projecting extensions 1^e of the sides 1^a. The member 3 is yieldingly depressed by means of a bowed spring 3^d one end of which is fastened to the plate 3^b, as shown, while its free end engages the plate 3, about centrally thereof, and tends to press said plate yieldingly upon the wiper 2 when the plate 3^b is lowered as shown in Figs. 1 and 2. The plate 3 may be held down by means of a bar 4 pivoted at 4^a on one of the sides 1^a above the table 1^b, and having its other end notched as at 4^b to engage under the head of a screw or stud 4^c on the other side 1^a as shown in Fig. 1. When it is desired to pass a film F through the machine the plate 3^b with presser 3 can be readily swung up to the position indicated in dotted lines in Fig. 2.

The rear end of the wiper 2 may be secured by means of a loop 2^f having its ends pivotally attached to the sides of the frame, the body of the loop being adapted to clamp the projecting end of the wiper 2 against the rear end of the table 1^b as shown in Fig. 2. The rear end of the wiper 2^a may be doubled back upon itself and under the front end of plate 3^b as indicated in Fig. 2.

The side members 1^a are extended above and beyond the front end of the table 1^a, as shown at 1^e, and are provided on their opposed faces with inwardly projecting brackets or bearing portions 1^f; and above the brackets 1^f the parts 1^e are provided with inwardly projecting vertical portions 1^g, the lower ends of which do not contact with the upper surfaces of the brackets 1^f; a sufficient space being left therebetween for the passage of the perforated edges of the film F; which edges rest upon and are guided by the members 1^e. The central portion of the film after it has been cleaned does not come in contact with the brackets. Journaled in the extension 1^e above the

brackets 1^e and at opposite sides of portions 1^f are film guiding rollers 5, which may be provided with collars 5^a opposite the brackets adapted to engage the perforated edges of the film F and hold same to prevent same buckling between the rollers.

The portions 1^f are provided with vertical bores 1^g above the projections 1^e and in these bores are placed wax sticks or fillers W, the lower ends of which sticks rest upon the perforated edges of the film F as shown in Figs. 2 and 4. The wax sticks are pressed down with yielding pressure by means of rods 6 inserted in the bores 1^g above the sticks, said rods being connected to a plate 6^a which has a central opening through which loosely passes a screw 6^b that is tapped through a threaded opening in a top bar 1^h connecting the upper ends of the portions 1^f. An expansion spring 6^c is strung on the upper end of screw 6^b between plate 6^a and a washer 6^d on the upper end of screw 6^b. Screw 6^b may be provided with a head piece 6^e by which it can be readily turned by hand. By adjusting the screw the wax W can be yieldingly forced down upon the perforated margins of the film with any desired pressure; and as the wax diminishes the screw 6^b can be tightened so as to maintain a substantially uniform pressure of the wax on the film.

Before the film is passed between the wipers 2 and 2^a it is preferably brushed so as to remove any dust therefrom and clean the perforations in its margins by passing it between brushes 7 and 8. These brushes 7 and 8 are shown as mounted on a bracket 8^a attached to the table 1^b as shown in Fig. 2 or other suitable support, and the brush 8 is secured between uprights 8^b attached to this bracket and may be detachably secured thereto in any suitable manner. As shown it is secured by means of a rod 8^c fastened by a thumb screw 8^d as shown in the drawing. The upper brush 7 may be similarly secured to the uprights 8^b by means of a rod 7^a and thumb nut 7^b, and members 8^b may be slotted as indicated at 7^c for the accommodation of the rod 7^a, and to permit the brush 7 to be adjusted vertically relatively to the brush 8, to regulate the pressure of the brushes upon the film passing therebetween.

When the machine is to be used, the film F is first passed between brushes 7 and 8, then between the cleaners 2 and 2^a, and then between the rollers 5 and brackets 1^e with the marginal edges passing under the wax sticks W; and as the film is drawn forward through the machine the brushes 7 and 8 sweep the film, and then the wipers 2, 2^a polish the film; and then the waxing devices wax the perforated margins of the film; as the brushes are yielding, and the wipers are held under spring pressure, and

the wax is held under spring pressure; all or any of these will yield or give when any patches or joints in the film pass without putting any undue strain upon the film and catching or tearing same. The yielding pressure of the wipers and wax prevents tearing of the film and at the same time the springs insure the desired and proper pressure of the wipers and wax upon the film to insure thorough cleaning and waxing thereof, while preventing tearing thereof.

If the film is new and does not need cleaning but only waxing, so that the perforated margins will not tear when being run through the projecting machine, the plate 3^b may be thrown up out of the way, as indicated in dotted lines in Fig. 2 and the film can then be waxed without being cleaned. The waxing device will wax the perforated margins of the film uniformly without scratching or otherwise injuring the film. The guide rollers prevent the film buckling or cracking while being waxed.

The operator can adjust the device for feeding the wax under spring pressure to a nicety so that just enough wax will adhere to the film to avoid friction of the film when run through the projecting machine, and this will obviate or materially lessen the cracking and snapping noises during the passage of a film through a projecting machine, as the wax keeps the perforated margins of the film moist or soft and prevents them breaking or cracking.

What I claim is:

1. In a machine for waxing photographic films, the combination of a frame, having opposite side members provided with brackets adapted to support the margins of a film, rollers mounted in said sides adapted to coöperate with said brackets and hold the margins of the film, wax holders on said side members above the brackets, rods entering said holders to expel wax therefrom, a plate connecting said rods, a spring for depressing said plate and rods, and a screw for regulating the tension of said spring.

2. In a machine for cleaning and waxing photographic films, the combination of brushes adapted to brush the film, means for wiping the film, means for guiding the film, and means for applying wax to the margins of the film.

3. In a machine for cleaning and waxing photographic films, the combination of brushes adapted to brush the film, means for wiping the film, means for guiding the film, wax receptacles adjacent the margins of the films, and spring means for projecting wax against the margin of the film.

4. In a machine for cleaning and waxing photographic films, the combination of brushes adapted to brush the film, means for wiping the film, means for guiding the film, wax receptacles adjacent the margins

of the films, spring-actuated means for expelling wax from the receptacles, and means for adjusting the pressure of said spring means.

5. In a machine for cleaning and waxing photographic films having perforated margins, the combination of brushes adapted to brush the film, means thereon for wiping the film, means for guiding the per-

forated margins of the film, wax receptacles 10 adjacent the margins of the films, rods for expelling wax from the receptacles, a spring for actuating said rods, and means for adjusting the tension of said spring.

In testimony that I claim the foregoing 15 as my own, I affix my signature.

RUPERT S. SCHEIBLEIN.
